Harry C. Grant, Jr., New York, N. Y., and Edmund Du Pont, Bloomfield, N. J., assignors to Specialties Development Corporation, Bloomfield, N. J., a corporation of New Jersey

Application August 5, 1942, Serial No. 107,818

Term of patent 14 years

To all whom it may concern:

Be it known that we, Harry C. Grant, Jr., a citizen of the United States, residing in New York city, in the county of New York, in the State of New York, and Edmund Du Pont, a citizen of the United States, residing in Bloomfield, in the county of Essex, in the State of New Jersey, have invented a new, original, and ornamental Design for a Flame Operated Switch or Similar Article, of which the following is a specification, reference being had to the accompanying drawing, forming a part thereof.

Figure 1 is an elevational view of a flame oper-

ated switch or similar article, embodying our new design.

Figure 2 is an elevational view thereof taken at right angles to Figure 1.

Figure 3 is a top plan view thereof.

Figures 4 and 5 are elevational views, corresponding to Figures 1 and 2, of the head or top piece of the switch.

We claim:

The ornamental design for a flame operated switch or similar article, substantially as shown.

HARRY C. GRANT, JR.
EDMUND DU PONT.
